The ornamental design for a bear shaped urn, as shown and described.

DESCRIPTION

FIG. 1 is a top view of a bear shaped urn;
 FIG. 2 is a left side view of the bear shaped urn;
 FIG. 3 is a front view of the bear shaped urn;
 FIG. 4 is a back view of the bear shaped urn;
 FIG. 5 is a bottom view of the bear shaped urn;
 FIG. 6 is a right side view of the bear shaped urn;
 FIG. 7 is a top perspective view of the bear shaped urn; and,
 FIG. 8 is a bottom perspective view of the bear shaped urn. The broken lines in FIGS. 5 and 8 depict the transition from a curved surface to a flat surface; the broken lines form no part of the claimed design.
